BLIND STITCHER

Carl G. Baehr, West Haven, Conn., assignor to
 The Greist Manufacturing Company, New
 Haven, Conn., a corporation of Connecticut

Application September 6, 1951, Serial No. 245,339

10 Claims. (Cl. 112—160)

1

This invention relates to a blind stitch attachment for sewing machines and more particularly to an attachment which may be readily applied to the ordinary household sewing machine in place of the usual presser foot, and which during the operation of the machine will effect a number of series of stitches in a straight line, and between two successive series of such straight-line stitches effect a zig-zag stitch at one side of the line of stitches.

It is often desirable to perform blind stitching, for example when a hem is to be made in a garment. To do this a straight line of stitching is made on the wrong side of the material which does not pass through to the outside and at intervals a stitch is made at one side of this line which does pass to the outside or catch the material of the hem so as to hold the hem in place. Such a stitch can be performed by what is usually termed a zig-zag stitch provided a number of straight stitches is made between the zig-zag stitches.

The present invention relates to a simple and effective attachment to the ordinary sewing machine by which blind stitching such as described above may be readily performed. This attachment is designed to be secured to the usual household sewing machine, and it is desirable, therefore, that it be simple in construction and that it be of relatively light weight and economically made so that it may be sold at a reasonable price.

As illustrated, the device comprises a frame to which is pivoted a lever having a cloth-engaging foot at its forward end, this foot engaging the cloth so as to move it laterally of the line of stitching when the foot is moved laterally or oscillated about its pivot. The device is so constructed that the cloth-engaging foot will for a series of stitches be restrained against movement and will then be given an oscillating movement or a lateral and return movement so as to make at least one stitch at one side of the line of stitches previously formed. By properly folding the material upon which the operation is being performed, this will result in a blind stitching operation upon a hem, for example.

One object of the invention is to provide a sewing machine attachment capable of effecting a blind stitch which may be readily attached to and used upon the ordinary household sewing machine.

A further object of the invention is to provide a blind stitch attachment for sewing machines, of simple construction which at the same time will be efficient in operation.

2

Still another object of the invention is to provide a blind stitch attachment for sewing machines having a pivoted lever provided at its forward end with a cloth-engaging foot and having a novel and simple mechanism for effecting oscillation of the cloth-holding foot about the pivot of the lever at the proper time in the operation of the device.

10 A still further object of the invention is to provide a blind stitch attachment for sewing machines of the type described in which the means for oscillating the lever carrying the cloth-engaging foot comprises a pair of slide members mounted on the frame of the attachment, each of these slide members having a cam surface to engage a part of the lever, the arrangement being such that when one of these cam members is moved in one direction, the other will be moved in the opposite direction, and in which structure means are operated by the usual fork arm is provided for actuating each of the slides in one direction and simultaneously permitting movement of the other side in the opposite direction.

25 To these and other ends the invention consists in the novel features and combinations of parts to be hereinafter described and claimed.

In the accompanying drawings:

Fig. 1 is a side elevational view of a sewing machine attachment embodying my invention;

Fig. 2 is a rear elevational view of the attachment;

Fig. 3 is a top plan view;

Fig. 4 is a bottom plan view;

Fig. 5 is a partial sectional view of the attachment on line 5—5 of Fig. 2;

Fig. 6 is a sectional view on line 6—6 of Fig. 5;

Fig. 7 is a view similar to Fig. 6 but showing the parts in another position; and

Fig. 8 is a perspective view of the actuating slides.

35 To illustrate a preferred embodiment of my invention I have shown in the drawings a sewing machine attachment comprising a sheet metal frame of substantially U-shaped form. This frame comprises a base plate 10 and a pair of upstanding side walls 11 and 12 upon which frame are supported the working parts of the device. An adaptor 13 is secured to the base plate 10 by means of which the attachment may be secured to the presser bar of the sewing machine.

40 Pivoted at 14 to the underside of the base plate 10 is an oscillatable lever 15, this lever carrying at its forward end a cloth-engaging foot 16, the lever being downwardly offset so that the foot

16 lies in a lower plane than the body portion 15 which lies flatly against the underside of the base plate 10. Upon the upper surface of the foot 16 a cloth guide 17, which serves to position the fold of the material, is pivoted at 17a for adjustment relatively to the foot.

Secured to the rear end of the lever 15 is a pin 18 which projects upwardly through an elongated opening 19 in the base plate 10 so that the lever 15 may oscillate to a limited extent about the pivot 14. The pin 18 is provided with a head 19a which stands in a position spaced upwardly from the base plate 10 of the frame, and it may also be noted that the pin 14 is likewise provided with a head 20 which is in spaced relation to and above the plate 10.

Slidably mounted upon the base plate 10 between the upstanding frame members 11 and 12 and guided thereby are a pair of slide members 21 and 22, which members are of similar form. Each of these slides, which lie flatly upon the base 10, is provided at its forward end with a cut-out portion 23 adapted to engage the body of the pivot pin 14 below the head 20, while each of the slides at its rear end is provided with a cam or beveled surface 24 adapted to engage one side of the pin 18 below the head 19a so that the latter will also serve to guide these members in movements along the surface of the base plate 10.

Leg members extend upwardly from each of the slides 21 and 22, each of these leg members having an inwardly inclined portion 25, an upwardly directed portion 26, and an outwardly and laterally directed portion 27, the portions 21 standing substantially in the same plane as shown in Fig. 2 of the drawings.

The cam surfaces 24 are so formed with respect to each other that when one of the slides (21, for example, as shown in Fig. 6) is in its forward position, the other slide, 22, must be in its rear position in order that the body of the pin 18 be received between them. When the slide 21 is moved from the position shown in Fig. 6 to that shown in Fig. 7, the cam surface 24 acting upon the pin 18 cams the rear end of the lever 15 laterally toward the opposite end of the slot 19, and the pin 18 acting upon the cam surface 24 of the lever 22 moves this lever forwardly to the position shown in Fig. 7. It will be seen, therefore, that when either of the slides is moved rearwardly, this connection between the slides and the oscillating lever 15 will cause the other one to move forwardly.

Rotatably mounted in the upstanding frame members 11 and 12 is a shaft 28 to which is secured a ratchet wheel 29. Upon this shaft is pivoted the usual fork arm 30, and upon the arm is pivotally mounted a pawl 31 urged into engagement with the teeth of the ratchet wheel 29 by a spring 32.

Secured to the shaft 28 between the frame members 10 and 11 are a pair of cam members 33 and 34, these members being spaced apart by a hub portion 35 of the shaft. As seen more especially in Fig. 5, the cam member 33 is provided with a pair of cam projections 36 that are substantially diametrically disposed, and the cam member 34 which is larger in diameter than the member 33 is provided with a pair of recesses 37 each of which is disposed opposite one of the projections 36. The cam members 33 and 34 are so disposed that the periphery of the cam member 33 will engage the laterally extending portion 27 of the slide 21 when the latter is in its forward position, as shown in Figs. 5 and 6.

while the periphery of the member 34 will engage the part 27 of the slide 22 when the latter is in its rearward position, as shown in Figs. 5 and 6. When one of the projections 36 strikes the part 27 of the slide 21, this slide will be moved rearwardly and at the same time the portion 27 of the slide 22 will be permitted to move into the recess 37 of the cam 34 so that the slide 22 may move forwardly.

It will thus be noted that each of the cams 33 and 34 engages one of the slides and moves this slide in a rearward direction. At the same time that this slide is moved in a rearward direction the cam which engages the other slide will permit movement of the latter in a forward direction.

It may also be noted that the cam projections 36 move the slide 21 in a rearward direction but only hold it momentarily in this position while the cam 34 maintains the slide 22 in its rearward position for the greater part of the period of operation of the device and only permits this slide to move forwardly when the laterally extended portion 27 is received in one of the recesses 37. Therefore, during the greater part of the operation of the device the parts will lie in the position shown in Fig. 6 when the slide 22 will be held in its rearward position and a line of straight stitches will be effected, while twice in every revolution of the shaft 28 of the cams 33 and 34 the position of the slides will be reversed, thus effecting a lateral stitch at one side of the line of straight stitches.

As will be apparent, the ratchet wheel 29 and shaft 28 are operated in a step-by-step movement by the fork arm 30, and at each step a stitch will be taken in the material by the descent of the needle bar. As illustrated, the ratchet wheel is provided with twelve teeth so that once in every six stitches one of the projections 36 will engage the portion 27 of the slide 21 and effect a lateral stitch. There will, of course, be five stitches in a straight line between these lateral stitches. During the effecting of the five stitches in a straight line, the portion 27 of the slide 22 will be in engagement with the unbroken periphery of the cam 34 so that the slides will be held in the position shown in Figs. 5 and 6.

While I have shown and described a preferred embodiment of my invention, it will be understood that it is not to be limited to all of the details shown, but is capable of modification and variation within the spirit of the invention and within the scope of the claims.

What I claim is:

1. A blind stitch attachment for sewing machines comprising a frame having a base member, a lever pivoted to said base member to oscillate about a vertical axis and having a cloth-engaging foot at its forward end, a pair of slide members slidably mounted on said frame and having cam means thereon adjacent the base member engaging said lever to oscillate it about its pivot, a fork arm pivoted on the frame, and means actuated by said fork arm to move said slide members.

2. A blind stitch attachment for sewing machines comprising a frame having a base member, a lever pivoted to said base member to oscillate about a vertical axis and having a cloth-engaging foot at its forward end, a pair of slide members slidably mounted on said frame and having cam means thereon adjacent the base member engaging said lever to oscillate it about its pivot, a fork arm pivoted on the frame, and means actuated by said fork arm to move said slide members,

said last-named means comprising a pair of cam members rotatably mounted on the frame, one engaging each of said slide members.

3. A blind stitch attachment for sewing machines comprising a frame having a base member, a lever pivoted to said base member to oscillate about a vertical axis and having a cloth-engaging foot at its forward end, a pair of slide members slidably mounted on said frame and having cam means thereon adjacent the base member engaging said lever to oscillate it about its pivot, a fork arm pivoted on the frame, and means actuated by said fork arm to move said slide members, said last-named means comprising rotatable cam means mounted on the frame and engaging said slide members to move them alternately in the same direction.

4. A blind stitch attachment for sewing machines comprising a frame having a base member, a lever pivoted to said base member to oscillate about a vertical axis and having a cloth-engaging foot at its forward end, a pair of slide members slidably mounted for horizontal movement on said base member, a fork arm pivoted on the frame, and means actuated by said fork arm to move said slide members, said lever having an upstanding projecting pin thereon and said slide members having cam means thereon engaging said pin on opposite sides thereof to oscillate the lever about its pivot.

5. A blind stitch attachment for sewing machines comprising a frame having a base member, a lever pivoted to said base member to oscillate about a vertical axis and having a cloth-engaging foot at its forward end, a pair of slide members slidably mounted on said frame and having cam means thereon adjacent the base member engaging said lever to oscillate it about its pivot, a fork arm pivoted on the frame, and means actuated by said fork arm to move said slide members, said last-named means comprising rotatable cam means carried by the frame and alternately engaging and disengaging said slide members to move one of said slide members in one direction and permit simultaneous movement of the other in the opposite direction.

6. A blind stitch attachment for sewing machines comprising a frame having a base member, a lever pivoted to said base member to oscillate about a vertical axis and having a cloth-engaging foot at its forward end, a pair of slide members slidably mounted for horizontal movement on said base member, a fork arm pivoted on the frame, means actuated by said fork arm to move said slide members, said lever having an upstanding projecting pin thereon, one of said slide members having a cam portion engaging one side of said pin and the other of said members having a cam portion engaging the other side of said pin to oscillate said lever about its pivot.

7. A blind stitch attachment for sewing machines comprising a frame having a base member, a lever pivoted to said base member to oscillate about a vertical axis and having a cloth-engaging foot at its forward end, a pair of slide members slidably mounted for horizontal movement on said base member, a fork arm pivoted on the frame, means actuated by said fork arm to move said slide members, said lever having an upstanding projecting pin thereon, one of said slide members having a cam portion engaging one side of said pin and the other of said members having a cam portion engaging the other side of said pin

to oscillate said lever about its pivot, and said fork-arm-actuated means engaging said slide members alternately.

8. A blind stitch attachment for sewing machines comprising a frame having a base plate, a lever pivoted to said plate to oscillate about a vertical axis and having a cloth-engaging foot at its forward end, a pair of slide members slidably mounted on said frame adjacent the base plate, a fork arm pivoted on the frame, said lever having an upstanding pin thereon, one of said slide members having a cam surface engaged with one side of said pin to move said lever in one direction, the other of said slide members having an oppositely disposed cam surface engaging the other side of the pin to move the lever in the other direction, a pair of cam members rotatably mounted on the frame and operated by the fork arm, and said cam members having means engaging said slide members to move them alternately in the same direction.

9. A blind stitch attachment for sewing machines comprising a frame having a base plate, a lever pivoted to said plate to oscillate about a vertical axis and having a cloth-engaging foot at its forward end, a pair of slide members slidably mounted on said frame adjacent the base plate, a fork arm pivoted on the frame, said lever having an upstanding pin thereon, one of said slide members having a cam surface engaged with one side of said pin to move said lever in one direction, the other of said slide members having an oppositely disposed cam surface engaging the other side of the pin to move the lever in the other direction, a pair of cam members rotatably mounted on the frame and operated by the fork arm, said cam members having means engaging said slide members to move them alternately in the same direction, and the movement of one of said slides in one direction effecting movement of the other slide in the opposite direction by engagement of said pin between said cam surfaces.

10. A blind stitch attachment for sewing machines comprising a frame having a base plate, a lever pivoted to said plate to oscillate about a vertical axis and having a cloth-engaging foot at its forward end, a pair of slide members slidably mounted on said plate, a fork arm pivoted on the frame, said lever having an upstanding pin thereon, one of said slide members having a cam surface engaged with one side of said pin to move said lever in one direction, the other of said slide members having an oppositely disposed cam surface engaging the other side of the pin to move the lever in the other direction, a pair of cam members rotatably mounted on the frame and operated by the fork arm, each of said cam members having a portion to engage and move one of said slides in one direction and a portion to disengage said slide to permit movement thereof in the opposite direction, and one of said cam members being disengaged from its corresponding slide when the other is engaged with the other slide.
